US00D548247S

(12) **United States Design Patent** (10) **Patent No.:** **US D548,247 S**
Lee (45) **Date of Patent:** **** Aug. 7, 2007**

(54) **PORTABLE VIDEO AND AUDIO
TRANSMISSION DEVICE**

(76) Inventor: **Jean Chin Chu Lee**, Room 6, 11th Floor, No. 410, Sec. 5, Jongshioi East Road, Taipei (TW)

(**) Term: **14 Years**

(21) Appl. No.: **29/260,985**

(22) Filed: **Jun. 6, 2006**

(30) **Foreign Application Priority Data**

Feb. 13, 2006 (TW) 95300680

(51) **LOC (8) CI.** **14-03**

(52) **U.S. Cl.** **D14/496; D14/159**

(58) **Field of Classification Search** D14/496, D14/137, 155–160, 168, 191, 195, 265; 375/240; 348/500, 545, 466; 386/125, 126, 95, 109; 370/389, 401, 468, 498; 340/539.1, 565–567; 455/344–347

See application file for complete search history.

(57) **CLAIM**

The ornamental design for a portable video and audio transmission device, as shown and described.

DESCRIPTION

FIG. 1 is atop, front and right side perspective view of a portable video and audio transmission device showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.
